US00D800150S

(12) United States Design Patent (10) Patent No.: US D800,150 S
Anzures et al. (45) Date of Patent: * Oct. 17, 2017

(54) DISPLAY SCREEN OR PORTION THEREOF WITH GRAPHICAL USER INTERFACE

(71) Applicant: Apple Inc., Cupertino, CA (US)

(72) Inventors: Freddy Anzures, San Francisco, CA (US); Alessandro Francesco Sabatelli, San Francisco, CA (US)

(73) Assignee: Apple Inc., Cupertino, CA (US)

() Term: 15 Years

(21) Appl. No.: 29/571,790

(22) Filed: Jul. 21, 2016

Related U.S. Application Data

(63) Continuation of application No. 29/496,728, filed on Jul. 16, 2014, now Pat. No. Des. 763,283, which is a continuation of application No. 29/424,282, filed on Jun. 10, 2012, now Pat. No. Des. 711,408.
